UNITED STATES PATENT OFFICE.

FREDERICK W. MYERS, OF PHILADELPHIA, PENNSYLVANIA, AND THOMAS H. MYERS AND WALTER MYERS, OF NEW YORK, N. Y.

LABEL PASTING AND APPLYING MACHINE.

SPECIFICATION forming part of Letters Patent No. 674,247, dated May 14, 1901.

Application filed February 9, 1901. Serial No. 46,636. (No model.)

To all whom it may concern:

Be it known that we, FREDERICK W. MYERS, of Philadelphia, Pennsylvania, and THOMAS H. MYERS and WALTER MYERS, of New York city, New York, subjects of the King of Great Britain, have invented certain Improvements in Label Pasting and Applying Machines, of which the following is a specification.

Our invention relates to certain improvements in label-pasting machines, particularly of the type known as "addressing-machines" for applying address-labels to letters and packages.

The object of our invention is to so construct the machine that it can be readily held in the hand and operated to feed the strip in contact with the pasting means by simply moving the device backward and forward over a surface and to cut the strip by a shear attachment which will press the detached label onto the letter or package.

In the accompanying drawings, Figure 1 is a perspective view of our improved label-pasting machine. Fig. 2 is a plan view. Fig. 25 3 is an end view. Fig. 4 is a side view. Fig. 5 is a longitudinal sectional view on the line 5 5, Fig. 2. Fig. 6 is a detail view showing the means for adjusting the paste-scraper. Fig. 7 is a view showing a holder for a rolled strip, and Fig. 8 is a view of a modification.

A is the frame of the machine, made of sheet metal in the present instance, and within this frame is a reservoir *a* for water, paste, mucilage, or other adhesive material. The frame 35 is preferably so proportioned as to be readily grasped by the hand, as indicated by dotted lines in Fig. 1, with the forefinger free, so as to actuate the shear. The frame is inclined at the forward end and is open at the top.

40 A' is a cover-plate for the top, pivoted at *a'* to the frame and having a slot *a'*, through which passes the label-strip *x*.

B is an endless belt which passes around a roller D, the trunnions *d'* of which are preferably detachably mounted in bearings in the frame A. On these trunnions are traction-wheels *d*, which in the present instance have rubber tires, so that when the machine is moved along a surface the wheels *d* will turn 45 and motion will be imparted to the roller D.

The belt passes from the roller D over guide-

rolls *e e* on an adjustable frame E and down into the paste-reservoir and around a guide-roll *e'*. The frame E is made as clearly shown in Figs. 5 and 6 and is held in its adjusted position by means of wing-nuts *e²*, which are mounted on the threaded stems *e³*, extending through the body of the case. Large washers *e⁴* are used, so that when the thumb-nuts secure the frame in its adjusted 55 position the frame will be rigidly held. The object of adjusting this frame is to take up the slack in the belt B and also to allow for the removal of the belt when it is necessary to clean the machine. The frame E can be 60 readily removed from the machine by detaching the nuts and screws.

It will be understood that these several rollers D, *e*, and *e'* are detachable, so that the belt can be removed from the reservoir and from 70 the machine. The frame E is suitably braced and is provided with a scraper *f*, which extends across the upper run of the belt B, so as to remove surplus paste or other adhesive material from the belt. This scraper *f* 75 can be either made fixed or adjustable. We prefer to provide means for adjusting the scraper as shown in Figs. 5 and 6, in which the scraper is pivoted at *f'* to the frame E and held in its adjusted position by a nut *f²* 80 on the screw-threaded trunnion. Other means of adjusting the scraper may be used without departing from our invention.

The top plate A' is pivoted at *a'* at the rear of the frame A, having trunnions which extend into slots, as clearly shown in the drawings. The opposite end of this plate A' is weighted at *a³*, and this weight may be of any size desired, according to the amount of pressure required to properly apply the adhesive 85 material to the strip, and the width of this end of the plate is made according to the width of the label. It is preferably made a little less in width than the label, so that when the label is applied the excess of adhesive material will not spread beyond the edge of the strip. Above the plate A' is a plate G, upon which the hand rests, and between this plate and the plate A' the strip of labels is passed, as shown in Fig. 1 and by 90 dotted lines in Fig. 5.

The plate G has arms *g* at each side, which

pass into sockets g' , secured to the sides of the frame A. The arms are reduced at g^2 , forming the shoulders which keep the plate G a sufficient distance above the plate A' to 5 allow for the passage of the strip. The plate, however, is readily removable, so that the device can be dismantled when desired.

In front of the frame A is a fixed blade C, preferably made detachable from the frame. 10 This blade is extended to one side, as shown in Fig. 1, and pivoted at c to this extension is a movable blade C'. This movable blade is also beveled and is held in contact with the blade C, so as to make a shear cut when 15 pressed down, severing the label to be pasted from the strip, as indicated in Fig. 1. A spring c' is secured at c^2 to the fixed blade and to the movable blade at c^3 and tends to keep the blade normally in the position shown 20 in the drawings.

Attached to the movable blade C' is a platen H, which has a flat cushion bottom h, so set in respect to the blade C' that when the platen, with the plate attached, is pressed down to 25 sever the label the platen will press the label onto the letter or parcel to be labeled, so that the label is held in place by the moist adhesive material. The upper portion of the platen H is made, as shown in the drawings, 30 so that when the finger is placed as shown by dotted lines in Fig. 1 and pressed down the tendency will be to force the movable blade against the fixed blade, so as to make a sharp cut and at the same time to press the platen 35 down onto the severed label.

In some instances where the labels are in rolls we may provide a holder for the roll, as shown in Fig. 7. This holder consists in the present instance of a frame I, having a section i, mounted in sockets i' on the body A, and pivoted to the section i at i^2 is a section i ^{3} , carrying the spindle i ^{4} , on which the roll is mounted. We preferably attach the portions i i ^{3} by a set-screw j, so that the frame 40 can be adjusted in any position desired, and on the spindle i ^{4} is a handle j' for rolling the strip when desired. This frame can be readily detached by simply pulling it out of the sockets i'. 45

It will be understood that while we have simply shown a side view in Fig. 7 of the frame the sections i i ^{3} are duplicated on the opposite side.

In Figs. 1 to 5 we have shown a device in 50 which the label is fed forward by moving the frame A forward, while in Fig. 8 we have shown a device where the label is fed forward by moving the frame back. We simply mount a small wheel d ^{2} on the spindles 55 of the roll D, and this wheel is in frictional contact with the traction-wheel d ^{3} or may be geared thereto, so as to allow the movement 60 of the frame to be reversed.

The operation of the machine is as follows: 65 The label is printed on short strips or in rolls, as desired, and if a strip is used, as shown in Fig. 1, the end of the strip is fed through a

slot a ^{2} and between the end of the plate A' and the belt B. Adhesive material is applied to the strip at the point of contact with the belt, and as the machine is moved forward the wheels d, being in contact with the surface over which the machine is moved, feed the belt forward, and the belt adhering to the label will feed the label also forward a sufficient distance to allow one complete addressed slip or label to be in position to be severed by the blades C C'. The finger is then pressed down upon the platen H, and the strip will be severed and pressed down upon the letter, 80 package, or other article to be labeled.

When the device shown in Fig. 8 is used, the machine is moved backward to feed the label.

It will be understood that while the device 85 shown is especially designed for use in labeling mail-matter it can be used for applying labels to any article. For instance, price-labels may be reeled upon such a machine and applied to articles of merchandise, and strips 90 of stamps may be applied when desired. It will be understood also that any suitable adhesive material may be used in the reservoir, and where the strip itself has adhesive material applied then water or other fluid may be 95 used to moisten the strip.

We claim as our invention—

1. The combination in a label-pasting machine, of an endless belt for feeding the label and applying adhesive material or moisture thereto, and means for imparting motion to the belt, the said means being constructed to be operated by being moved parallel to, and in contact with, the surface of the article upon which a label is to be pasted, substantially as described.

2. The combination in a label-pasting machine, of an endless belt for feeding the label and applying adhesive material or moisture thereto, and a traction-wheel for feeding said belt, substantially as described.

3. The combination in a label-pasting machine of a body, a reservoir therein, an endless belt extending into the said reservoir, a traction-wheel for driving said belt when the device is moved along a surface, a guide for a label-strip so that on the movement of the device the label will be fed and adhesive material or moisture applied thereto, substantially as described.

4. The combination in a label-pasting machine of a body, a reservoir therein, an endless belt extending into the reservoir, a guide for guiding a label-strip into contact with the belt, a traction-wheel for driving the said belt, and a shearing device for cutting the label after it has been fed forward, substantially as described.

5. The combination in a label-pasting machine of a body, a reservoir therein, an endless belt extending into the reservoir, a guide for guiding a label-strip into contact with the belt, a traction-wheel for driving the said belt, a shearing device for cutting the label after

it has been fed forward, said shearing device having a platen thereon for pressing the label onto the article, substantially as described.

6. The combination in a label-pasting machine of a body having a reservoir therein, a belt, guide-wheels for directing the belt into the reservoir, and a label-guide for guiding the label into contact with the belt, one of the rolls for the belt having traction-wheels thereon, and a severing device for cutting the label, substantially as described.

7. The combination in a label-pasting machine, of a body, a reservoir in the rear portion of the body, an inclined plate, a belt 15 partly inclined, guide-rolls for the belt adjustably secured to the body so that the belt can be removed therefrom, rolls in the bottom of the body for carrying the belt, a plate attached to the body having in it a slot forming a guide for the label-strip, the said plate pressing said strip against said belt, and shears for cutting the label-strip after it has been projected, substantially as described.

8. The combination in a label-pasting machine, of a body, a reservoir therein, an endless belt, a traction-wheel for driving said belt, a detachable cover-plate for the body pivoted to the rear thereof, and weighted at its free end, said plate having a slot in it 25 through which the label-strip passes into contact with the belt, substantially as described.

9. The combination in a label-pasting machine, of a body, a reservoir therein, an endless belt, a traction-wheel for driving said belt, a detachable cover-plate between which 35 and the top plate the label is guided, substantially as described.

10. The combination in a label-pasting machine, of a body having at one end a blade 40 secured thereto, and having at the opposite end a reservoir, an inclined plate forming the front wall of the reservoir, a roller in the reservoir, a roller at the front of the machine

with means for turning the same constructed to be operated by being moved over the article upon which a label is to be pasted, a pair of rollers near the upper edge of the inclined plate, an endless belt guided by said rollers, and a guide for the strip, a movable blade acting with the fixed blade to sever the strip, 45 substantially as described.

11. The combination in a label-pasting machine of a body, a feed-roller at the forward end of the body, a reservoir at the rear end, an inclined plate forming the front wall of 55 the reservoir, a guide-roller in the reservoir, and guide-rollers above the reservoir near the upper edge of the inclined plate, a frame pivoted to the body for supporting the guide-rollers whereby the said rollers may be simultaneously adjusted toward or from the other rollers and means for securing the frame in the adjusted position, and a guide for the strip, substantially as described.

12. The combination in a label-pasting machine of a body, a reservoir in the body, an endless belt guided through the said reservoir, a feed-roller around which the belt passes, traction-wheels for driving said feed-roller, a frame for carrying the two guide-rolls for the 70 belt, and a scraper adjustably secured to the said frame, substantially as described.

In testimony whereof we have signed our names to this specification in the presence of two subscribing witnesses.
